Primary Examiner — Clare E Heflin(74) *Attorney, Agent, or Firm* — Peter T. DiMauro; GE Global Patent Operation(57) **CLAIM**

The ornamental design for an indirect luminaire, as shown and described.

DESCRIPTION

FIG. 1 is a bottom perspective view of an indirect luminaire; FIG. 2 is a right perspective view of the luminaire of FIG. 1; FIG. 3 is a front elevation view of the luminaire of FIG. 1; FIG. 4 is a rear elevation view of the luminaire of FIG. 1; FIG. 5 is a right elevation view of the luminaire of FIG. 1; FIG. 6 is a left elevation view of the luminaire of FIG. 1; FIG. 7 is a bottom plan view of the luminaire of FIG. 1; and, FIG. 8 is a top plan view of the luminaire of FIG. 1. References to "right", "left", "front", "rear", "top", and "bottom" in the figure descriptions are not meant to require certain in-use orientation; a luminaire according to the claimed design may be used in any orientation. The shade lines in the Figures show contour and not surface ornamentation.
